UNITED STATES PATENT OFFICE

2,493,642

CUPOLA TYPE FURNACE

Edward Summers Renshaw, Upminster, and Sidney James Sargood, Ilford, England, assignors to Ford Motor Company, Dearborn, Mich.

Application March 26, 1945, Serial No. 584,774
In Great Britain June 6, 1944

2 Claims. (Cl. 266—32)

1

It is customary practice to line the hearth and vertical stack of the furnace with acid or basic refractories and the length of the operating time of the furnace depends mainly on the extent of fusion and erosion of the refractory materials employed. Such fusion and erosion are most severe in the zone immediately above the tuyères in which maximum combustion of the coke fuel occurs and the face of the refractory lining is in consequence exposed to a temperature at or near the fusion point of the refractory. Moreover, slag erosion becomes severe in this region owing to the refractory being at a temperature near its softening point.

In view of the foregoing it is found that with cupola type furnaces as hitherto constructed the operative period of the furnace is very short with the result that the furnace must be continually shut down to enable the necessary repairs to be effected.

The object of the present invention is to prolong the operating time of the furnace and so increase its output while at the same time reducing the labor and material required for maintenance. A further advantage of the invention is that it permits of a more positive control of slag composition owing to the amount of refractory that is absorbed by the slag being so small as to be practically negligible.

The invention consists in a cupola type furnace in which the wall in the neighborhood of the tuyères is lined with a cast steel or other metal lining adapted to be cooled by the application of cooling medium thereto.

The invention also consists in a cupola type furnace in which the combustion and melting zone between the hearth and the stack is of conical form tapering inwards towards the stack, the base of such zone immediately above the tuyères being formed of or lined with a cast steel or other hollow structure, the interior of which is supplied with a cooling medium.

The accompanying drawing illustrates in part sectional elevation in one convenient form of cupola type furnace constructed in accordance with the invention.

In carrying our invention into effect in one convenient manner, we form our cupola type furnace with a conventional stack 1 (only a portion of which is shown extending about as far as the usual charging floor level) and hearth 2, but in place of forming the combustion and melting zone portion 3 as a vertical continuation of the stack as is usual, we make this zone of conical form as shown with its base supported by a series

2

of steel gussets 4 or other supports arranged at convenient intervals beneath the said base. The distance between the tuyères 5, and the point where the conical section 3 meets the stack 1 is determined by the coke bed height with which it is normal to operate, but by way of example it may be noted that in one cupola of this type, the normal coke bed height may be 46 inches above the tuyères and the cone height above the tuyères 5 would be 42 inches. The portion of the furnace wall between the base of the refractory cone portion 3 and the inner edge of the tuyères is lined with a series of cast steel or other metal segments 6, there being conveniently one of said segments 15 for each tuyère, and the base of each such segment forming the upper portion of the tuyère. Here again, however, it will be understood that this arrangement is purely by way of example and that any other suitable arrangement may be adopted. The contour of each segment approximates to the line of erosion in the area of the furnace in which it is located and each segment is made hollow so that water or other cooling medium may be admitted thereto. In the particular 20 construction illustrated the cooling medium is supplied to the segments through the cooling pipes 7 from a supply main, so that each segment has a separate feed and each also has a separate outlet 8, all the outlets 8 leading to a suitable waste means. Moreover, baffle plates are preferably fitted internally of the cooler segments to ensure satisfactory circulation of the cooling medium and the latter may be recirculated by a suitable return system if desired. The shape of the 25 cooling segments may be varied to suit individual requirements.

The tuyères 5 are connected through ducts 9 with the wind box 10 to supply the air required for operation. As is customary, the hearth is hinged at 11 to permit dumping of the cupola residue. A sand bottom may be laid on the hearth and the metal withdrawn through the usual iron notch 12, while a cinder notch permits withdrawal of the slag. The cupola itself is made with the steel shell or casing 13 and the usual refractory lining 14, except in the immediate vicinity of the tuyères where they are replaced by the segments 6 which are filleted in place by refractory material 16.

It will be seen that the refractory face which is subject to maximum heating and erosion has been removed to a position remote from the tuyère inlet in order to ensure that the refractory will be subject to temperatures below the softening point 55 of the refractory. Moreover, the angle of inclina-

tion of the refractory face is such as to prevent the slag and molten metal formed during melting from flowing over the refractory face itself and attack from these sources is therefore negligible. Preferably, the minimum diameter of the section immediately above the tuyères is greater than the diameter at the top of the conical portion 3, thus preventing any direct flow of metal from impinging on the surface of the coolers.

As a result of the foregoing improvements, it has been found that the operating period of the refractory is at least 15 times as long as that obtainable with furnaces hitherto constructed with the result that not only is there considerable economy in material and labor required for maintenance, but also greater tonnages can be handled, without the necessity for shutdown repairs, and furthermore, the negligible amount of refractory absorbed by the slag enables a more positive control of slag composition to be obtained.

In basic lined, as distinct from acid lined cupolas, the advantages are perhaps more evident in that basic materials have a higher initial cost and basic patching materials are limited in variety. Moreover, when operating with basic linings, control of slag composition becomes more important in that a greater degree of desulphurization and dephosphorization is possible with a controlled slag. In addition, it now becomes possible to line the conical portion with acid refractory, the cooling segments acting as a neutral parting layer.

In practice, the cooling segments may be coated with a thin layer of refractory not exceeding 1" in thickness, or alternatively, they may be painted with a coating of refractory wash.

It will be understood, however, that the invention extends broadly to cupola type furnaces in which the wall in the neighborhood of the tuyères is formed of, or lined with, a cast steel or other metal structure adapted to be supplied with cooling medium and is therefore not to be limited to the foregoing details of construction which are given purely by way of example to indicate the nature of the invention and not to limit its scope.

Having now particularly described and ascertained the nature of our said invention and in what manner the same is to be performed, we declare that what we claim is:

1. A cupola comprising a stack, tuyères, a crucible and a hinged hearth, said stack being

approximately cylindrical and resting upon a supporting structure having the shape of a truncated cone and sloping inwardly towards said stack, the top of said tuyères being formed by a series of hollow metallic cooling segments which are surrounded by the base of said supporting structure, said hollow metallic cooling segments having inner surfaces which slope inwardly towards the crucible and being arranged in the form of a circle the least diameter of which is greater than the diameter of the stack, that portion of the lining of the cupola immediately above the hollow metallic cooling segments being acidic in character and the lining below the hollow metallic cooling segments being basic in character whereby the hollow metallic cooling segments act as a neutral parting layer.

2. A cupola the lining of which is partially acidic and partially basic, said acidic lining being separated from said basic lining by a hollow metallic member adapted to receive internally cooling media and which acts as a neutral parting layer between the acidic lining and the basic lining whereby undesirable chemical reaction between the acidic and basic lining is prevented, said hollow metallic member being located immediately above the tuyères of the cupola.
